(57) CLAIM

The ornamental design for a game board, as shown and described.

DESCRIPTION

FIG. 1 is a front, top, right perspective view of a cornhole game showing my new design;

FIG. 2 is a right side elevational view thereof;

FIG. 3 is a left side elevational side view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines depicting portions of the cornhole game form no part of the claimed design.
